CONTROL SWITCH

Application filed May 3, 1928. Serial No. 274,774.

This invention relates generally to a control switch for use in electrical circuits, and more particularly to a control switch especially adapted to control the starting, stopping and reversal of an electric motor.

The principal object of this invention is to improve upon the control switch disclosed in my copending application Serial No. 136,246, filed September 18, 1926. Another object of this invention is to provide a control switch to which an electric motor is alertly responsive, that is simple in operation and construction, and that has a high degree of efficiency and low power loss.

Another object of this invention includes the provision of a switch and operating means associated therewith, whereby the control circuit of an electric machine may be closed, opened or reversed at any time by the operator, including means whereby the circuit may be opened and the machine stopped automatically at predetermined times.

Another object includes the provision of an improved automatic motor stopping device operating in cooperation with an element driven by the motor, the operating device being adjustable and adapted to be set to stop the motor at predetermined times in accordance with the setting of the device.

Other objects of this invention will be in parts obvious and in part pointed out hereinafter.

In accordance with this invention, my electric switch device is interposed between a suitable power source and the electric machine to be controlled. My switch device consists generally of two terminal carrying plates or blocks, one plate being pivoted for pendulum-like swinging movement over the side face of the other plate, which remains stationary. A set of electric terminals are disposed along the lower edge of the swinging plate, which are adapted to be swept into contact with either one of two sets of electric terminals disposed along the side face of the stationary plate. Contact between the swinging set of electric terminals and one of the stationary sets throws the motor into operation in one direction and contact between the swinging set of terminals and the second sta-

tionary set reverses the direction of motor rotation. If the swinging set of terminals contacts neither of the stationary sets, the switch is open and no current flows through the motor. Manual means are provided for moving the swinging plate with its set of terminals into contact with either set of the stationary terminals. Spring elements operate to hold the swinging plate in out-of-electric contact position with the stationary plate, and it is only moved from this position by the manual means above mentioned. An electro-magnetic latch device is provided to lock the switch in either contact position, both manual and automatic means being provided for releasing the latch to permit the switch to be restored by the spring elements to out-of-contact position.

The automatic means for releasing the latch consists generally of a pair of spring pressed switch buttons, one for each direction of motor rotation, normally in open switch position. A rotating plate, properly geared down and driven by the motor, carries a projecting element which is adapted to strike either switch button to close the latch circuit after the plate has been rotated through a predetermined angle, to release the latch, to permit the switch device to move to non-contact position, stopping the motor. One switch button is thus operative to stop the motor when rotating in one direction, and the other switch button is operative to stop the motor when rotating in the opposite direction.

In order that a clearer understanding of my invention may be had, attention is hereby directed to the accompanying drawings, forming a part of this application and illustrating certain possible embodiments of my invention.

In the drawings, Fig. 1 discloses a side view of my control switch and the associated automatic latch operating device, the electric motor controlled thereby and the wiring arrangement therefor being illustrated diagrammatically;

Fig. 2 is a front elevation of my control switch, showing in particular the spring elements for normally retaining the switch in

out of contact position, and the manually operated means for swinging the switch into either of two contact positions;

Fig. 3 is a fragmentary vertical cross-sectional view of my switch device, showing in particular the interior construction of the swinging terminal carrying plate, taken on line 3—3 of Fig. 1; and

Fig. 4 is a fragmentary detail taken on line 4—4 of Fig. 1.

Similar reference characters refer to similar parts throughout the several views of the drawings.

Referring to Fig. 1, I have illustrated diagrammatically a motor 1 and a wiring arrangement, the motor being electrically connected by the wiring to my control switch 2. An automatic stop device 3 for stopping the motor and driven thereby releases at predetermined times a latch device associated with the control switch, which permits the control switch to swing to off contact position, stopping the motor.

For purposes of illustration, I have shown my automatic stop device as connected to the motor 1 by means of suitable belting 4 and a pulley wheel 5, the pulley wheel being geared to a revolving stop disk 6 of the stop device. More particularly, the pulley wheel 5, fixed to shaft 7, turns worm gear 8. Worm gear 8 rotates large beveled gear wheel 9, fixed to shaft 10. Small gear wheel 11, fixed to shaft 10, rotates large gear wheel 12, fixed to shaft 13. Small gear wheel 14, fixed to the end of shaft 13, rotates worm gear 15, fixed to shaft 16, which carries the rotating disk 6. Thus, it is seen that, by the above system of reduction gearing, the stop disk is made to revolve at the desired speed.

Bracket 17, secured to any suitable support, carries a switch block 18. A contact button, comprising a head portion 19 and a stem portion 20, forms one contact terminal of the automatic stop device. A screw member 21, fixed to the switch block and aligned with the contact button, forms the other contact terminal of the stop device. The contact point 22 of the contact button may be held out of electric contact with contact point 23 of the screw member 21 by means of a coil spring 24 seated within a cavity 25 in the switch block and pressing against a collar 26 on the stem portion 20 of the contact button. A roller 27, made of some non-conducting material, such as fibre, projects laterally from the edge of revolving disk 6 and is adapted to strike head portion 19 to move the contact button, against the action of coil spring 24, into electric contact with screw member 21. The roller 27 may be secured in any desired position around the disk 6 by providing a groove 6' having an enlarged cavity into which the head portion of stud member 27' is adapted to seat. A cap member 27" screws onto the stud member 27' to

clamp the stud firmly to the disk 6 when adjusted in the desired position. Fibre roller 27 is freely rotatable on the neck portion of cap member 27".

To automatically stop a motor adapted to be operated in either direction, I provide a duplicate stop device, comprising a switch block 28 having a screw member 29 as one electric terminal and a switch button comprising a head portion 30 and a stem portion 31 as the other terminal. Reverse rotation of the motor and pulley wheel 5 driven thereby moves roller 27 into contact with the head portion 30 of the switch button carried by block 28, closing the contacts and stopping the motor, as will be described hereinafter. Since the period of motor rotation is measured by the time it takes the roller 27 to move from the stop position at one block to the stop position at the other block, it is seen that the period of motor rotation can be lengthened or shortened by changing the positions of the blocks relative to each other around the circumference of the disk. By sliding stud member 27' around in its groove 6', the roller 27 may be so positioned on the disk as to properly contact the head portions 19 and 30 of the respective switches, whatever their relative position along the circumference of the disk may be.

The switch for controlling the operation of the motor 1, and consequently the rotation of the disk 6, will now be described. A terminal carrier 33, in the form of a plate or block secured to a suitable support 34, has supporting standards 35, one fixed as by screws 36 to each end thereof. The standards are preferably made wish-bone or forked in shape, the ends of the forks being secured to the terminal block 33. A second terminal carrier 36, in the form of a plate or block, is suspended over the terminal block 33 by means of pins 37 projecting laterally from the side edges of the block and journaled in the standards 35. The upper face 38 of the terminal block 33 is slightly concave, as shown in Figs. 2 and 3, permitting the terminal block 33 to swing thereover with a pendulum-like movement.

Blocks 33 and 36, made of non-conducting material, have electric terminals mounted thereon. A cross-piece 39 secured to the top of the standards 35 carries a series of electric terminal securing elements 40, 41, 42 and 43. Electric conductors 44, 45, 46 and 47 connected to the respective terminal elements extend part way into holes extending through the terminal block, as shown in Figs. 1 and 3. Contact terminals *a'*, *b'*, *c'* and *d'* placed in the holes in the terminal block 36 slidably project from the lower edge thereof. Each of the contact terminals *a'*, *b'*, *c'* and *d'* has an upwardly projecting stem portion 48 to which the respective conductors 44, 45, 46 and 47 are connected. A coil spring 48' 130

positioned around the stem 48 and held in place by screw-cap 36' screwed into the top of the block 36 resiliently holds the respective terminals in projected position.

5 Terminal block 33 is shown as provided with two sets of electric terminals extending through the block, each set aligned in a row and having contact points lying flush with the top face of the block. The contact terminals *a*, *b*, *c* and *d* of one set are arranged in a row along one side of the block, and the contact terminals *e*, *f*, *g* and *h* of the other set are arranged in a row along the other side of the block. Spring elements 49 and 50 fixed 10 to the sides of block 33 are adapted to resiliently contact each side of swinging block 36 to normally hold it in vertical suspended position. In this position the contact terminals in block 36 are disposed between the rows of contact terminals in block 33 and out 15 of electric contact therewith.

Means are provided for sweeping the swinging set of electric terminals into contact with either of the stationary sets. Arms 25 51 and 52, fixed to swinging block 36, extend laterally from each side thereof. Adjacent the ends of the oppositely extending arms 51 and 52 plungers 53 and 54 are positioned, provided with collars 55 and 56. The plungers are normally held in upward position 30 by means of coils 57 and 58, which are compressed between the collars and the frame or base of the switch. Each plunger is also provided with a striking collar 59 and 60 35 adapted to respectively engage pins 61 and 62 projecting from the ends of arms 51 and 52. Now it is seen that, by depressing either plunger 53 or 54, the striking collar of the actuated plunger will engage the adjacent 40 arm to swing the block 36 in the corresponding direction. The amount of this swinging movement given to the block 36 is sufficient to bring the set of contacts carried by the block into electric contact with the corresponding set of contacts of the stationary 45 block 33.

Means are provided for latching the block 36 in the electric contact position to which it has been swung. The latching means is substantially the same as that described in my co-pending application above referred to, including a relay comprising magnet coils 63 and an armature 64, which carries a pin 65 slidably supported in suitable brackets 66. A coil 55 spring 67 surrounding the pin 65 and compressed between the armature 64 and the rear bracket yieldingly holds the armature forward. The end of pin 65 projects through the forward bracket and is adapted, under 60 the action of spring 67, to latch against either side of a lug 68 which is secured to the rear edge of swinging block 36.

The amount of movement given to the swinging block by means of the plungers will 65 move the lug 68 sufficiently to cause latch pin

65 to engage against one side or the other thereof, holding the corresponding sets of terminals in contact and preventing return movement of the swinging plate to neutral non-contact position until the latch pin has 70 been retracted, as by energization of the relay coils 63. The arrangement of the plungers and projecting arms is such that one will not interfere with the proper operation of the other.

75 The circuits and the operation of the switch will now be described. When the block 36 is in normal position, held so by spring elements 49 and 50, none of the terminals carried thereby contacts any of the terminals on the stationary block 33. In this adjustment the motor is at rest and no current passes through the coils of the relay. To start the motor rotating in one direction or the other, it is merely necessary to depress the corresponding plunger 53 or 54. If plunger 53 is depressed, collar 59 will strike arm 51 to swing block 36 about its pivot elements 37, sweeping terminals *a'*, *b'*, *c'* and *d'* carried by block 36 80 into contact with terminals *a*, *b*, *c*, and *d* carried by block 33. The circuit will be as follows. From one terminal 69 of a suitable source of supply, current will flow through conductor 70 and terminal *a'*. From terminal *a'* current will flow across to terminal *a*; 85 thence through conductor 71 to one pole 72 of the motor armature; and thence from the other pole 73 of the motor armature through conductor 74 to the opposite terminal 75 of the source of supply. Meanwhile, current will 90 also flow from pole 72 of the motor through conductor 76 to terminal *c'*, across to terminal *c*, through conductor 77 to the field terminal 78 of the motor. After passing through the motor, the current flows from the field terminal 79 through conductor 80 to terminal *b*, across to terminal *b'*, and thence through conductors 81 and 74 to the opposite terminal 75 95 of the source of supply.

100 Assuming that in this adjustment of the switch, the motor drives the rotating disk counterclockwise, moving roller 27 into contact with head portion 19 to close the stop switch after a predetermined number of revolutions of the motor, the relay will thus be 110 automatically energized and the pin 65 retracted to permit block 36 to swing back into normal non-contact position, in accordance with the following circuit. Relay operating current will flow from one terminal 82 of a 115 suitable source of low voltage current, as a battery 83, through conductors 84 and 85, to contact point 22, thence to contact point 23 through conductor 86 to terminal *d*, across to terminal *d'*, and through conductor 87 to the 120 relay coils 63. From relay coils 63, the current flows through conductor 88 to the opposite terminal 89 of the battery 83. It is, therefore, seen that, as soon as the motor has 125 made a predetermined number of revolutions, 130

terminal points 22 and 23 are brought into contact and the relay coils 63 will be energized to retract latch pin 65, permitting block 36 to swing into non-contact position to stop the motor.

Manual means are provided to permit the operator to stop the motor at any time. A manually operative switch 90 is connected in circuit with the battery 83 and the relay, so that when the switch 90 is closed the relay is energized to retract pin 65, as heretofore described. Current flows from terminal 82 of battery 83, through conductors 84 and 91, through the switch 90, through conductor 92, 15 to the relay coils 63, and thence through conductor 88 to the opposite terminal of the battery.

To cause the motor to rotate in the reverse direction, rotating the disk 6 clockwise, it is first necessary to stop the motor if it is 20 rotating. Plunger 54 is then depressed to sweep terminals *a'*, *b'*, *c'* and *d'* into contact with terminals *e*, *f*, *g* and *h*. In this event, the latch pin 65 will engage against the opposite side of the lug 68. In this adjustment 25 of the switch, the armature circuit for the motor will be as follows. From terminal 69 of a suitable power source, through conductor 70, through terminal *a'*, across to terminal *e*, through conductor 93 to terminal *a*, through conductor 71, and thence, as before, through the armature of the motor to the supply terminal 75.

The motor field circuit will then be reversed to reverse the direction of motor rotation, and will be as follows: from conductors 71 and 94 to terminal *c'*, across to terminal *g*, across through conductor 95 to terminal *b*, and thence through conductor 96 to the field terminal 79. From the opposite field terminal 78, the current flows through conductor 77 to terminal *c*, thence across through conductor 97 to terminal *f*, across to terminal *b'* through conductors 81 and 74 to the opposite terminal 75 of the source of supply. Similarly, in this adjustment of the switch, the relay coils 63 will be energized to permit block 36 to swing into non-contact position when roller 27 has 50 moved clockwise sufficiently to strike head portion 30 to close the relay circuit. In this case current from the battery 83 will pass from terminal 82 through conductor 84 through terminals 31 and 29 of the stop switch, through conductor 98 to terminal *h*, across to terminal *d'*, through conductor 87 to the relay, from whence the current passes through conductor 88 to the opposite pole of the battery. The motor may be stopped in 55 its rotation at any time by merely closing the circuit at switch 90, as before.

My motor control device is especially adapted for use in connection with an electric motor driving the reels for motion picture film, so that the film may be wound

back and forth from one reel to another. In such case, the reels may be so mounted as to be driven by pulley wheel 5 driven by the motor, which is rotated first in one direction a predetermined number of times and then rotated in the opposite direction a like number of times, producing corresponding number of revolutions of the respective reels. However, it will be understood that the utility of my switch control is not limited to controlling motors driving motion picture reels, but that it may be used to control the movement of electric machines generally. It is further understood that I do not limit myself to the use of two sets of terminals, or any specific number of terminals, in the stationary switch block; but as many terminals and sets may be used as there are movements to be controlled.

From the above disclosure, it is seen that my switch is simple and compact and adapted to be mounted in any convenient position on the machine with which it is to be used. Good and firm electrical contact is insured between terminals carried by one block and the terminals carried by the other, with consequent danger of arcing reduced to a minimum.

As many changes could be made in the above construction and as many apparently widely different embodiments could be made without departing from the scope thereof, it is intended that all matter contained in the above description or shown in the accompanying drawings shall be interpreted as illustrative and not in a limiting sense.

What I claim is:—

1. In a switch of the character described, in combination, a pair of carriers, a set of electrical terminals fixed to the periphery of one of said carriers, a plurality of sets of electrical terminals fixed to a side face of the other of said carriers, means for normally retaining one of said carriers in out-of-electrical contacting position in reference to the other carrier, and means for rotating one of said carriers with respect to the other in either direction from said normal position to place the terminals thereon into and out of contact selectively with the terminals of the other carrier.

2. In a switch device of the character described, in combination, a pair of carriers, a set of electrical terminals arranged in a row along one of said carriers longitudinally, a plurality of sets of terminals each set arranged in a row along the other of said carriers longitudinally, means for normally retaining one of said carriers in out-of-electrical contacting position in reference to the other carrier, and means for sweeping one carrier transversely in either direction from said normal position over the other to place the terminals thereon in and out of contact selectively with the terminals on the other carrier.

3. In a switch device of the character described, in combination, a pair of supporting standards, a carrier hinged along one edge to said standards, an electric terminal fixed to the free edge of said hinged carrier, a cross-piece connecting said standards, electrical conductors fixed to said cross-piece and leading to said electric terminal, a stationary carrier, a plurality of electric terminals fixed to a side face of said stationary carrier, and means for sweeping the terminal edge of the first mentioned carrier across the terminal face of the other to place one terminal in and out of contact selectively with another. 5
4. In a switch device of the character described, in combination, a pair of carriers arranged in planes at an angle one to another, a set of electric terminals fixed to an edge of one of said carriers and arranged in a longitudinal row, a plurality of sets of electric terminals fixed to a side face of the other of said carriers, each set of said terminals being arranged in a longitudinal row with each terminal lying substantially flush with the side face 20 of said carrier, and means for sweeping the terminal edge of the first mentioned carrier across the terminal face of the other to place one set of terminals in and out of contact selectively with another set. 15
5. In a switch device of the character described, in combination, a carrier hinged along one edge, a set of electric terminals housed in a longitudinal row within said carrier and projecting from the free edge thereof, resilient means associated with each of said terminals tending to force its terminal outwardly, a stationary carrier, a plurality of sets of electric terminals fixed to a side face of said stationary carrier, and means for sweeping the terminal edge of the hinged carrier across the terminal face of the stationary carrier to place one set of terminals in and out of contact selectively with another set. 25
6. In a switch device of the character described, in combination, a pair of supporting standards, a carrier hinged along one edge to said standards, an electric terminal positioned along the opposite edge thereof, a cross-piece connecting said standards, a flexible electrical conductor fixed to said cross-piece and leading to said electrical terminal, a stationary carrier, a plurality of electric terminals fixed to a side face of said stationary carrier, means for sweeping the terminal edge of the hinged carrier transversely across the terminal face of the stationary carrier to place one set of terminals in and out of contact selectively with another set, means for normally retaining the hinged carrier in one position, and means for locking said carrier in a position out of normal position. 30
7. In a switch device of the character described, in combination, a carrier hinged along one edge, an electric terminal positioned
- along the opposite edge thereof, a stationary carrier, a plurality of electric terminals fixed to a side face of said stationary carrier, and means for sweeping the terminal edge of the hinged carrier across the terminal face of the stationary carrier to place one set of terminals in and out of contact selectively with another set, said means including an arm extending laterally from said hinged member, a manually operative plunger cooperating with said arm to rock said hinged carrier and resilient means associated with said plunger operative to return the plunger when released to normal arm disengaged position. 70
8. In a switch device of the character described, in combination, a carrier hinged along one edge, an electric terminal positioned along the opposite edge thereof, a stationary carrier, a plurality of electric terminals fixed to a side face of said stationary carrier, means for sweeping the terminal edge of the hinged carrier across the terminal face of the stationary carrier to place one set of terminals in and out of contact selectively with another set, spring elements normally retaining said terminals in out-of-contact position, and means for releasably holding various pairs of said terminals in various contact positions, said means including an arm projecting laterally from each side of said hinged block, and a spring pressed plunger associated with each of said arms. 80
9. In a switch device of the character described, in combination, a frame, a carrier suspended from said frame, an electrical terminal fixed to the free end of said carrier, a stationary carrier, a plurality of electric terminals fixed to a side face of said stationary carrier, means for sweeping the terminal end of said suspended carrier across the terminal face of said stationary carrier to place one terminal in and out of contact selectively with another terminal, and resilient means positioned on each side of said hinged carrier to normally retain said hinged carrier in out-of-terminal contacting position. 100
10. In a switch device of the character described, in combination, a frame, a block hinged at one edge to said frame, a set of electric terminals resiliently projecting from a free edge of said block, a stationary block, a plurality of sets of electric terminals fixed to a side face of said stationary block, and means for rocking said hinged block to sweep the set of terminals carried thereby into and out of contact with various sets of terminals carried by the stationary block, said means including an arm projecting laterally from each side of said hinged block, and a spring pressed plunger associated with each of said arms. 115
11. A switch device for controlling the operation of an electric device including, in

combination, a pair of carriers for electric terminals operatively connected to said electric device in such a manner that rotation of one of said carriers with respect to the other will move certain sets of electric terminals into contact to cause said electric device to operate in one direction and rotation of said carrier in the opposite direction will move other sets of electric terminals into contact to cause said electric device to reverse its operative direction, a latch device for locking the respective sets of terminals in the various contact positions, and electromagnetic means for releasing said latch.

15 This specification signed this 28th day of April, 1928.
